UNITED STATES PATENT OFFICE

105,360

DESIGN FOR AN ICE CREAM SCOOP

Roland Allen Cameron, Ottawa, Ontario, Canada

Application January 11, 1937, Serial No. 67,006

Term of patent 14 years

To all whom it may concern:

Be it known that I, Roland Allen Cameron, a citizen of the Dominion of Canada, residing in the city of Ottawa, county of Carleton, Province of Ontario, Dominion of Canada, have invented a new, original, and ornamental Design for an Ice Cream Scoop, of which the following is a specification, reference being had to the accompanying drawing, forming part thereof.

In the drawing, Fig. 1 is a perspective view of the ice cream scoop, showing my design;

Fig. 2 is a top plan view;
Fig. 3 is a bottom plan view; and
Fig. 4 is a cross-sectional view taken along line 4—4 of Fig. 3.

I claim:

The ornamental design for an ice cream scoop, as shown.

ROLAND ALLEN CAMERON.
